COUPLER MECHANISMS FOR RAILWAY VEHICLES

Filed Sept. 28, 1945

UNITED STATES PATENT OFFICE

2,466,860

COUPLER MECHANISM FOR RAILWAY
VEHICLESPaul F. Paig, Monongahela, and Paul M. Volk,
Bell Vernon, Pa.

Application September 28, 1945, Serial No. 619,202

2 Claims. (Cl. 213—175)

1

This invention relates to improvements in coupler mechanisms for solid axle vehicles such as open hearth charging buggies and mine and quarry cars and particularly to a combination draw-bar and coupler mechanism for mine cars and similar industrial cars.

One object of the invention is to provide a coupler mechanism of comparatively simple, inexpensive construction and design wherein the draw-bars of two cars are provided with hook-shaped ends capable of automatically interlocking with one another on trackage having curves running as high as 90° curvature.

More specifically, the invention contemplates the provision of mechanism in which both coupling members are pivoted for vertical swinging motion on cooperating car bumpers and in which one of said members is allowed a lateral swinging movement with respect to its bumper, said members having hook-shaped ends which will compensate, so to speak, for track curvatures by reason of both of said hook-shaped ends themselves being of arcuate formation transversely of the car bumpers whereby the mechanism of two buggies or cars can be automatically coupled at all times, thus minimizing the risk of operatives being injured in coupling operations.

Still another object of the invention is to assure a firm interlocking engagement of the hook-shaped ends of cooperating male and female couplers. This is attained by forming said coupler ends with undercut, transversely curved surfaces with the undercut surface of one coupler of convex formation and the other of concave formation. Preferably, the hook-shaped end of the couplers are also provided with beveled exterior faces which initially engage each other in coupling two cars together whereby the beveled surface of one coupler will ride over that of the other to facilitate bringing the two couplers into interlocking engagement.

With these and other objects in view the invention consists in certain details of construction and combinations and arrangements of parts, all as will hereinafter be more fully described and the novel features thereof particularly pointed out in the appended claims.

In the accompanying drawings—

Figure 1 is a top plan view of the ends of two cars illustrating the present coupler mechanism;

Fig. 2 is a side elevation of the coupler;

Fig. 3 is a detail sectional view on the line 3—3 of Fig. 1; and

Fig. 4 is a sectional view on the line 4—4 of Fig. 2.

2

Fig. 5 is a sectional view transversely of the male coupler on the line 5—5 of Fig. 1.

In the present instance the coupler members, indicated at 10, 11, also serve as radius or draw-bars and for this reason they are mounted directly on the tops of the car bumpers. The bumpers comprise top plates 12, 12^a, on which the coupling members are mounted and the usual front walls 13 but, otherwise, the bumpers may vary in construction depending upon the presence or absence of draft gear (not shown) and the type of the draft gear, if used.

While both coupling members are of hook-like construction, member 11 will be referred to as 15 the male member and member 10 as the female member for purposes of this description. The female member is comparatively broad or wide and is formed at its inner end with slots 14 for reception of the heads of bolts 15 which project above 20 and are attached to the bumper plate 12^a, cotter pins preferably being used to prevent accidental displacement of the bolts. A pivot pin 16 extends transversely through the upwardly projecting bolt heads and the ears formed on member 10 25 by the slots 14 and thus the outer end of the coupler member 10, which normally rests on plate 12^a, is permitted a free upward swinging movement in a vertical plane. The inner or rear end of male member 11 is formed with a single 30 slot 14^a for reception of a headed bolt 15^a which is swiveled in and projects above bumper plate 12. A pivot pin 16^a extends transversely through said bolt head and the outer end of this coupler member 11, which normally rests on plate 12, is allowed to swing in a vertical plane and as the bolt 35 15^a is free to turn in the bumper plate, this male member is also capable of swinging in a horizontal plane. Hence, the mechanism as a whole is especially adapted for use on vehicles having rigidly supported wheel axles because the male member can not only swing laterally but the free outer ends of both couplers are capable of swinging vertically upward from the plates on which they are normally supported. Lateral swinging 40 movement of the male member is limited by a cross piece 11' fast on said member and provided with depending ends 11^a adapted to serve as stops when they contact the side edges of bumper plate 12.

The outer or free end of female coupler 10 is in the form of a hook with the outer face 17 of the hook beveled and inner face 18 undercut for interlocking engagement with the free end of male coupler 11 which is also in the form of a hook, 55 having a beveled outer face 17^a and an undercut

inner face 18^a. Thus, when two cars are moved into coupling position the beveled faces 17, 17^a of the hook shaped ends of the two elements will ride past each other to permit the male member hook to drop into interlocking engagement with the female member hook. Preferably the member 11 is provided with a hand grip 19 for facilitating uncoupling of the cars.

As previously stated, female member 10 is quite broad compared with the breadth of male member 11 and for the purpose of permitting relative transverse movement of the two members while coupled to compensate for curves in the trackage over which the cars travel and to permit the cars to be automatically coupled while occupying curved portions of the trackage the inner face 18 of member 10 is of concave curvature transversely of said member.

Another feature of the present coupling is the specific formation of the hooked ends of the coupler members or the manner in which the inner faces of the hooked ends of said members are recessed. In view of the fact that the coupler members also function as draw-bars, the hooked ends are produced by forming a comparatively long recess in the top face of the female coupling member 10 and dishing the bottom wall 20 of said recess longitudinally of the member. This dished surface of said female member is of segmental shape, describing an arc of approximately 60° and is engaged by the beveled outer face 17^a of the hook of the male member 11, said beveled face preferably being of convex formation longitudinally of the member and of a curvature substantially corresponding to that of the dished bottom surface 20. Thus, under buffing conditions, the hooked ends have sufficient amplitude of longitudinal movement to insure their returning to interlocking engagement when the coupling members are again subjected to draft conditions.

The longitudinally dished surface 20 of the female member 10 terminates at its forward end at the base of the undercut inner face of the hooked end of the member and to insure firm, intimate contact between the inner undercut surface of each hook with the inner face of the other when subjected to draft strains, the inner face 18 of member 10 is not only curved or of concave formation transversely of the member, as previously described but is also of dished or concave formation vertically or longitudinally while the inner face 18^a of the hook of male member 11 is of convex curvature both laterally and longitudinally or vertically. Not only does this specific structure insure intimate contact of the combination coupler and draw-bar members when under draft but it facilitates relative lateral movement of the members when they are under draft and the cars are moving along curved trackage. Preferably, the width of the female coupler is such that the curved edge of the merging inner and outer faces 17, 18 is approximately 90° in length.

In connection with the convex curvature of the inner face 18^a of the hook of male member 11 and the concave curvature of face 18 of female member 10, it will be further appreciated that this specific formation of these faces permits the same not only to be made of comparatively large area but also insures their intimate contact throughout their entire area. As a result, the members function as draw-bars with maximum

efficiency in the sense that draft strains are distributed over a large area as distinguished from the localization of such strains as occurs where coupler hooks have a line or point contact with cooperating coupling members.

Thus, it will be appreciated that the present construction of coupler is not only comparatively simple and inexpensive for production purposes but performs a combination of functions with maximum efficiency, such as permitting automatic coupling on curved tracks thus eliminating possibility of injury to operatives; compensating for track curvatures and vertical irregularities in trackage while the cars are in motion; and notwithstanding heavy draft strains while serving as radius or draw-bars without danger of the interlocking hooked ends being fractured or damaged.

What is claimed is.

1. In a coupler mechanism for cars of the character described comprising two bumpers, a male coupler member pivoted at its inner end on one bumper with its outer end free to swing both vertically and horizontally with respect to said bumper, said outer end being of hook-shaped formation with a beveled outer surface and an inner undercut face of convex curvature transversely of the bumper, and a female coupler member having its inner end pivotally mounted on and above the other bumper with its outer end free to swing vertically above said other bumper, the outer end of said female member being of hook-shaped formation and adapted to interlock with the hook of the male coupler, the hook-shaped end of said female member having an undercut inner surface of concave curvature transversely of the bumper, the curvature of the inner surface of the coupler members being formed on corresponding radii.

2. In a coupler mechanism for cars of the character described comprising two bumpers, a male coupler member on one bumper, a female coupler member on the other bumper, said female coupler having its inner end pivotally supported on its bumper with its outer end normally resting on its bumper but free to swing in a vertical plane above its bumper and said male coupler having its inner end pivotally supported on its bumper with its outer end normally resting on its bumper but free to swing in a horizontal plane and in a vertical plane above its bumper, each coupling having a hook-shaped end comprising an outer surface and an undercut inner surface intersecting said outer surface to form a laterally extending edge, the edge and undercut surface of one coupling being of convex curvature transversely of the bumpers and the edge and undercut surface of the other member being of concave curvature transversely of said bumpers.
